UNITED STATES PATENT OFFICE.

WILLIAM EDWARD HOLMES MORSE AND OLIVER HAMMOND BEMIS, OF ALGONA, IOWA.

COMBINATION-LOCK.

SPECIFICATION forming part of Letters Patent No. 684,082, dated October 8, 1901.

Application filed May 20, 1901. Serial No. 61,082. (No model.)

To all whom it may concern:

Be it known that we, WILLIAM EDWARD HOLMES MORSE and OLIVER HAMMOND BEMIS, citizens of the United States, and residents of 5 Algona, in the county of Kossuth and State of Iowa, have invented a new and Improved Combination-Lock, of which the following is a full, clear, and exact description.

The invention relates to combination-locks 10 such as shown and described in Letters Patent of the United States No. 662,285, granted to us November 20, 1900.

The object of the present invention is to provide a new and improved combination 15 door-lock arranged to permit the owner to readily set the outside knob to a desired combination to prevent unauthorized persons from opening the door, to permit of rendering the combination device ineffective when 20 ever it is desired to use the door-lock the same as an ordinary door-lock, and to allow of using the device for sounding an electric alarm on the door-bell.

The invention consists of novel features and 25 parts and combinations of the same, as will be fully described hereinafter and then pointed out in the claims.

A practical embodiment of the invention is represented in the accompanying drawings, 30 forming a part of this specification, in which similar characters of reference indicate corresponding parts in all the views.

Figure 1 is a cross-section of the improvement as applied. Fig. 2 is a sectional rear 35 elevation of the same on the line 2 2 in Fig. 1. Fig. 3 is an enlarged face view of the outside knob with the cover therefor removed, and Fig. 4 is a sectional plan view of the same on the line 4 4 in Fig. 3.

In the door A is arranged the usual door-lock B of any approved construction and adapted to be operated by the inner section C of a divided spindle, the outer section C' of which is adapted to be locked to the inner 45 section, so that the spindle can be turned from either the outside or the inside to unlock the door. The inner spindle-section C is provided with a knob D and the outer spindle-section is mounted to turn and to slide 50 transversely in a hub E, projecting from a casing E', attached to or forming part of an

escutcheon E², secured to the outside of the door in the usual manner. On the outer spindle-section C' is secured or formed a knob F, containing a combination mechanism which 55 normally prevents the knob F and the spindle-section C' from being moved inward to engage the spindle-section C' with the spindle-section C, so that unauthorized persons cannot open the lock upon turning the knob 60 F; but a person knowing the combination mechanism can bring the knob into such position that it can be pushed transversely to engage the inner end of the outer spindle-section C' with the spindle-section C to turn 65 the latter, and thereby unlock the lock and open the door. For the purpose mentioned the adjacent ends of the spindle-sections C C' are provided with a groove C² and a tongue C³, respectively, normally out of engagement, 70 but moved into engagement when the spindle-section C' is moved transversely in an inward direction, as above explained. The grooved end of the spindle-section C is provided with a pin C⁴, adapted to abut against 75 the face of the door and prevent the spindle-section C from being drawn out of position in the door-lock, and a similar pin C⁵ is on the inner end of the spindle-section C' to limit the outward-sliding movement of 80 said spindle-section by the pin abutting against the inner face of the casing E'. The pin C⁵ has its upper portion pressed on opposite sides by the free ends of arms C⁶, fulcrumed in the casing E' and pressed on by 85 springs C⁷, so as to hold the free ends of the arms C⁶ in engagement with the pin C⁵, as shown in Figs. 1 and 2. The spring-pressed arms C⁶ hold the knob F in a normal position; but said arms allow a transverse sliding of 90 the pin C⁵ and the spindle-section C' for the purpose previously mentioned. The lower portion of the pin C⁵ is adapted to be engaged by a slide C⁸, mounted to move up and down in the casing E' to hold the tongue C³ 95 in engagement with the groove C² at the time the spindle-section C' is in an innermost position. The slide C⁸ is provided with a button C⁹, extending through an elongated slot E³ to the outside of the casing E', so that 100 when the section C' is in an innermost position and the operator pushes the button C⁹

upward, then the slide C⁸ moves in front of the lower end of the pin C⁵, so that the spindle-section C' is prevented from outward movement. When the several parts are in this position, the door can be opened by turning either of the knobs D or F the same as in ordinary door-locks.

On the outer end of the hub E is formed an annular flange E⁴, extending part way into an annular groove F', formed on the back of the knob F, and said annular flange E⁴ normally abuts against the rear face of a plurality of slides G, mounted to move in radial grooves F², formed on the face of the knob F. (See Figs. 3 and 4.) Each of the slides G is formed on its rear face with a groove G', adapted to register with the flange E⁴ when the slide is moved into proper position, and when all the slides G are in registering position then the knob F, with the spindle-section C', can be moved inward to bring the tongue C³ in engagement with the groove C² to connect the spindle-sections with each other and allow the operator on turning the knob F to unlock the lock B, and thereby permit of opening the door. As stated, the slides G are, with their grooves G', normally out of register with the flange E⁴, so that the knob F cannot be moved in an inward direction until the slides G are moved by the operator to bring their notches G' in register with the flange E⁴, and in order to accomplish this the following device is provided: Each slide G is pressed into an innermost position by a spring G²; but the inward movement of the slide is limited by a lock-tooth G³ on the slide and engaging a pin H, adapted to be set by the operator in one of a row of apertures H', extending in the direction of the corresponding guideway or groove F² in the knob F, as indicated in Figs. 3 and 4. On the top of each slide are formed parallel ratchet-tooth racks G⁴ G⁵, of which the rack G⁴ is adapted to be engaged by a spring-pawl I, fulcrumed at I' on the face of the knob F, as is plainly illustrated in Fig. 3. Each pawl I is formed at its outer end with an elongated slot I², engaged by a pin J', secured to a button J, mounted to slide in a radial guideway F³, formed in the knob F, and the inner end of each button J is pressed on by a spring J², so as to hold said button normally in an outermost position. When the operator presses the button J in an inward direction, then the pin J' imparts a swinging motion to the pawl I, so that the latter imparts an outward sliding movement to the rack G⁴ and the slide on which the rack is secured, the slide G moving outward against the tension of the spring G². When the operator releases the pressure on the button J, then the spring J² returns the button J, the pin J', and the pawl I to their former positions, it being understood that the arrangement is such that on inward pressure of the button J the pawl I moves the slide forward a distance corresponding to the length of a

tooth on the rack G⁴. The other rack G⁵ is engaged by a spring-dog K, secured to the face of the knob F, so that when the operator has pressed the button J inward and moved the slide outward, as described, then the dog K engages a tooth on the rack G⁵ and holds the slide against return movement when the pressure on the button J is released. When the operator presses the button a second time, the above-described operation is repeated—that is, the slide G is again moved outward and locked in an outermost position against return movement by the dog K. When the several slides G are in their normal positions, the grooves G' are out of register with the flange E⁴, the spindle-section C' is held in the outermost position, (shown in Figs. 1 and 4,) and the flange E⁴ abuts against the rear faces of the slides, and consequently the spindle-sections are out of engagement.

In order to move the slides the desired distance to bring the grooves G' into register with the flange E⁴, the operator successively presses and releases the buttons J the desired number of times to bring the slides G into such outermost position that their grooves G' register with the flange E⁴. It is understood that by the use of the pins H and teeth G³ each slide can be set in such a position that a notch or groove G' of the slide is a different distance away from the flange E⁴ than the other slides, and consequently the buttons J have to be pressed and released a different number of times, so as to bring the several slides into proper position. When this has been done, the operator can move the knob F inward to engage the spindle-section C' with the spindle-section C and turn the latter on turning the knob F to unlock the lock B and permit of opening the door.

In order to reset the several slides G, the following device is provided: Under the spring-paws I and the spring-dogs K extend the outer ends of levers L L', fulcrumed on the knob F and adapted to be engaged at their inner forward ends by an annular flange N' on a button N, mounted to slide on a post F⁵, forming part of the knob F. When the button N is pressed in an inward direction, a swinging motion is given to the several sets of levers L L', so that their forward ends lift the pawls I and the dogs K out of engagement with the racks G⁴ G⁵, whereby the latter are immediately pushed inward against their pins H by the action of the springs G². The hub of the button N is provided with a slot N², engaged by a pin N³, secured on the post F⁵ to allow the said button N to slide on the post, but to prevent it from turning thereon. On the annular flange N' of the button N is secured or formed a contact-arm O, adapted to make contact with a contact-screw O', held on an insulated block O², secured to the knob F, as is plainly shown in Figs. 3 and 4. An insulated wire O³ leads from the contact-screw O' through a bore F⁶ in the knob F and the spindle-section C' to connect with

a battery P and an alarm door-bell Q, the return-wire O⁴ being connected with the casing E' or other metallic part of the lock, making electric connection with the knob F, button 5 N, and contact-arm O. When the button N is pressed for releasing the slides G, as previously explained, then at the same time the contact-arm O moves in contact with the contact-screw O', so as to close the circuit for the 10 alarm door-bell and sound the latter. Thus the lock can be made use of to ring the door-bell by pressing the button N. By having the pin N³ engaging the slot N² the contact-arm O is always held in proper position relatively to the contact-screw O' to make contact when the button N is pressed. It is understood that the button N is held normally in an outermost position by the levers L L'. (See Fig. 4.) The knob F is provided with a 15 suitable cover or hood F', through which extends the shank of the button N, the cover serving to protect the working parts of the knob from dust, moisture, &c.

Having thus fully described our invention, 20 we claim as new and desire to secure by Letters Patent—

1. A door-lock having a divided spindle, the inner section of which engages the door-lock mechanism and the outer section of which 25 is mounted to slide transversely and is adapted to be moved in engagement with the inner section, to work the door-lock mechanism for opening the door from the outside, a pin on the outer spindle-section, and a slide under the control of the operator and adapted 30 to move to the rear of said pin, to hold the outer spindle-section in engagement with the inner spindle-section, as set forth.

2. A door-lock having a spindle made in sections, one of which engages the door-lock 35 mechanism and the other is adapted to be moved in engagement with the first section, an escutcheon-hub in which the slidable spindle-section is mounted to turn and to slide, a knob on said slidable spindle-section, spring- 40 pressed slides mounted to move in guideways on said knob and having grooves adapted to register with said hub, each slide having a number of parallel ratchet-tooth racks, a spring-pressed pawl for engaging one of the 45 racks of a slide, a button under the control of the operator, for imparting a swinging motion to said pawl, a spring-dog for engaging the other rack of a slide, levers extending under said pawl and dog, an electric circuit having a fixed contact on said knob, a contact 50 on said button and normally out of engagement with the first-named contact, a door-bell in said circuit, and a button under the control of the operator and adapted to be 55 moved in engagement with said levers, to impart a swinging motion thereto and release said pawls and dogs from said racks, to allow the slides to return by the action of their springs, said button also moving its contact 60 in engagement with the other contact, to close the circuit and sound the door-bell, as set forth.

In testimony whereof we have signed our names to this specification in the presence of 65 two subscribing witnesses.
